UNITED STATES PATENT OFFICE.

DEWEY F. ADAMS, OF PROVIDENCE, RHODE ISLAND.

DESIGN FOR A BADGE OR BREASTPIN.

SPECIFICATION forming part of Design No. 15,756, dated February 3, 1885.

Application filed December 8, 1884. Term of patent 3½ years.

To all whom it may concern:

Be it known that I, DEWEY F. ADAMS, of the city and county of Providence, and State of Rhode Island, have invented and produced 5 a new and original Design for a Badge or Breastpin; and I hereby declare the following specification, taken in connection with the accompanying drawings, forming a part of the same, to be a description thereof.

10 In the accompanying drawings, Figure 1 represents a face view of a badge or breastpin embodying the design. Fig. 2 shows an edge view of the same.

The badge or breastpin consists of two members, A and B. The member A is a disk of 15 circular form, and its face is crossed by arcs of circles a and a' , extending in opposite directions, thereby giving to the disk the appearance of the "globe" or "world." The

member B is in the form of a band, ribbon, or 20 scroll, extending across the face of the member A and projecting beyond the perimeter of the same, and may be used for the reception of letters or words.

What I claim, and desire to secure by Letters Patent, is—

The design for a badge or breastpin, consisting of the member A, circular in form, and representing the "globe" or "world," and the member B, in the form of a band, ribbon, 30 or scroll, extending across the face of the member A and projecting beyond the perimeter of the same, substantially as described and shown.

DEWEY F. ADAMS.
